UNITED STATES PATENT OFFICE.

JAMES POLLOCK, OF NEW YORK, N. Y.

BOILER FOR UTILIZING FINE COAL.

Application filed February 26, 1927. Serial No. 171,241.

This invention relates to a steam boiler in which the furnace is adapted for burning fine fuel, such as fine coal and coal dust, in suspension. The type of furnace employed 5 is that illustrated in my Patent No. 1,530,-321; dated March 17, 1925, in which the interior of the furnace chamber is circular in cross section and flares upwardly, and the air and fuel are blown upwardly in the 10 chamber through a nozzle and the fuel is held in suspension in the chamber until consumed.

In the present invention, the furnace chamber is arranged centrally within an 15 outer enclosing wall, an annular steam drum is arranged above the chamber, and an annular container extends downwardly from said drum in the space between the chamber and the outer wall. The furnace chamber 20 is open at the top and a hollow header extends over the chamber a short distance from its upper end. This header communicates with the container and with the steam drum. The header and container, filled 25 with water, form baffles which direct the gases from the top of the furnace chamber downwardly along its outer side, and the gases then flow upwardly in the space between the container and the outer wall, and 30 thence pass through flues above the header into the stack. Tubes arranged in a circular series extend downwardly from the header, and tubes in another circular series extend downwardly from the steam drum 35 into the path of the gases flowing around the container, and these tubes are connected to the lower part of the container. The gases in flowing to the stack come in contact with the header and thence flow down- 40 wardly between the container and the wall of the furnace chamber, and after passing under the container the gases flow upwardly on its outer side and thence under the drum to the stack. It is necessary to maintain 45 a balanced pressure over the top of the furnace chamber, in order to prevent the fuel from being drawn out of the chamber before it is consumed. This is controlled by a damper in the stack and by valves in the 50 air pipe, and also by causing the gases which flow over the top of the furnace chamber to take a downward course.

The air necessary for combustion of the fuel and for maintaining it in suspension 55 is pre-heated in the stack, and is forced by

a pump, in regulated quantity, through the nozzle and also into pockets which are provided in the furnace wall, and from these pockets, where the air becomes heated to a high temperature, the air flows through 60 passageways into the furnace chamber, at points some distance above the nozzle. This pre-heating of the air gradually increases the efficiency of the furnace.

The arrangement of the furnace and 65 boiler is such as to conserve the heat to the greatest extent.

In the accompanying drawing,

Fig. 1 is a central vertical section through the boiler;

Fig. 2 is a horizontal section on the line 70 2-2 of Fig. 1; and,

Fig. 3 is a partial horizontal section on the line 3-3 of Fig. 1.

Referring to the drawing, *a* represents 75 the outer wall of the furnace, which is cylindrical in form, and *a'* indicates the base of the furnace, these parts being made of suitable refractory material and contained within a cagelike structure composed of vertical channel bars 1, the top and bottom plates 2 and 3, the structure as a whole being supported upon legs or standards, one of which is shown at 4. In the central part of the furnace is arranged a combustion 80 chamber *b* of the type shown in my Patent No. 1, 530,321; dated March 17, 1925. The interior wall 5 of this combustion chamber flares upwardly and outwardly, as shown, and in the lower end of the chamber is arranged 85 a nozzle 6, through which fine fuel is blown upwardly by air which is forced into the nozzle through a pipe 7. The fuel is fed to the nozzle by mechanism not shown, through a pipe 8.

In the upper part of the furnace an annular steam drum *c* is arranged, this drum fitting closely within the furnace wall, and a stack *d* fits within the space surrounded by the inner wall of the drum, the drum and stack together extending over the entire space enclosed by the outer wall of the furnace. An annular container *e* extends downwardly from the drum around the combustion chamber to a point near the lower end 90 thereof, and this container is spaced from said chamber in order to provide an annular passageway 9 for gases which flow over the top of the combustion chamber. The container is also spaced from the base 105 110.

a', as shown, to permit the gases to pass under the container. The container is connected at its upper end to the steam drum and at its lower end to a circular series of water tubes 10, arranged between the container and the wall of the combustion chamber, and also to a circular series of water tubes 11, arranged vertically in an annular passageway 12 between the container and the outer wall *a* of the furnace. As shown, the tubes 10 are connected to the container by T's 10^b, and the tubes 11 are connected to the container by T's 11^b, and these T's are in line with short tubes 22, extending horizontally through the wall of the furnace and provided with caps 22^a. By removing these caps, a tool may be inserted through the tubes to clean out the connections between the vertical tubes and the container. The upper ends of the tubes 11 are connected to the annular drum *c*, as shown, and their lower ends extend through the lower wall of the furnace chamber and are provided with suitable caps 11^a. A hollow header *f* is secured to the inner wall of the container *e* and arranged a short distance above the top of the combustion chamber, and the series of tubes 10 communicate at their upper ends with the interior of this header, as shown in Fig. 1. The lower ends of these tubes extend through the bottom of the furnace chamber and are closed by suitable caps 10^a. The inner wall of the annular container also has openings 13, at suitable intervals, which establish communication between the interior of the header and the interior of the annular container. A pipe 14 leads upwardly from the top wall of the header and has branches 14^a which connect the interior of the header with the interior of the annular drum *c*.

A plurality of flues 15 extend through the upper part of the container, above the header *f*, and these flues form passageways 45 through which gases may flow from the annular passageway 12 into the stack *d*. The course of the gases from the combustion chamber to the stack is indicated by the arrows. These gases flow over the top of the combustion chamber, thence downwardly through the annular passageway 9 to the bottom of the container *e*, thence under the container and upwardly through the passageway 12 to the flues 15, and from thence 50 through the stack.

In the lower part of the outer wall of the furnace is arranged a plurality of horizontal passageways 16, in which are fitted doors 17, which may be opened to clean out the 55 sediment settling on the bottom wall of the furnace, and sight openings 18 are provided through which the attendant may observe the flame and determine whether the combustion is going on properly in the combustion chamber, or whether a change in the

air or fuel feed, or in the draft, is desirable to make the combustion more perfect.

In the stack, which is relatively short, is arranged a pre-heater *g*, and at the upper end of the stack is arranged an adjustable damper *h*, the pre-heater and damper being in all respects the same as in my co-pending application, Serial Number 135,222, filed Sept. 13, 1926. The air for supporting combustion is supplied by a pump *k*, which is connected by a pipe 19 to the pre-heater *g*, and from the pre-heater branch pipes 20 lead downwardly to points below the bottom of the furnace, and the ends of these branch pipes extend into arcuate pockets 21 in the wall of the combustion chamber. From these pockets small openings 23 lead through the wall into the combustion chamber, these openings or passageways being preferably tangential to the axis of the combustion chamber, so that the air passing into the combustion chamber will cause a swirl of gases and fuel therein. The air is heated in the pre-heater *g* and also in the pockets 21, before it enters the furnace. It is found that the pre-heating of the air greatly increases the efficiency of the furnace, and as the wall of the combustion chamber becomes very hot, the air, in passing through the pockets in the wall of the furnace becomes heated to a high degree.

In operation, the fine coal and coal dust, which is fed through the pipe 8, is blown upwardly in the combustion chamber through the nozzle 6, by air which is carried from one of the pipes 20 through pipe 7 to the nozzle. The air pressure is sufficient to maintain the fuel in suspension in the combustion chamber, as explained in my Patent No. 1,530,321. For igniting the fuel, one or more oil burners *m* are provided in the lower part of the combustion chamber, and after the fuel has become ignited these burners are cut off. The draft through the furnace is controlled so that the pressure in the combustion chamber will not be reduced below atmospheric pressure, as a partial exhaustion of the combustion chamber would interfere with the maintenance of the fuel in suspension until consumed and would cause some of the unconsumed fuel to pass over the top of the combustion chamber. The gases must flow downwardly from the top of the combustion chamber through the passageway 9, and the damper is arranged so as to retard the flow of gases through the stack so that a balanced pressure is maintained over the combustion chamber, and the fuel, with proper regulation of the air flow, will be maintained in the combustion chamber until it is practically consumed, and nothing but the fine ash will pass over the top of the combustion chamber. The heat is utilized to the fullest extent as the combustion chamber is in the center of the

boiler and the flame and gases in passing to the stack are in direct contact with the header *f*, tubes 10, annular container *e*, tubes 11, and also with the steam drum *c* and with the connections from the header to the drum.

The operator, by looking through the sight holes in the clean-out doors, can determine by the appearance of the flame passing below the annular container whether the combustion is complete, or whether it can be improved by admitting more air, or more fuel, or by regulating the position of the damper to control the draft. The air may be regulated by a suitable hand valve in the air pipe, and the fuel may be regulated by changing the rate of feed. If sediment collects in the bottom of the furnace it can be removed through the clean-out doors, and the vertical tubes in the furnace may be cleaned by removing the caps 10^a and 11^a, on the bottoms of the tubes. Water may be supplied to the furnace through a pipe connection which may be made to the lower end of any one of the vertical tubes. The connections 10^b and 11^b between the annular container and the tubes 10 and 11, respectively, may be cleaned by removing the caps from the horizontal tubes 22 which are in line with said connections.

20 What I claim is:

1. In a steam boiler, a vertically arranged combustion chamber, open at the top and having an upwardly flaring inner surface, an outer wall spaced from and surrounding the combustion chamber and extending above the same, a base connecting said chamber and wall, an annular steam drum, fitting within the upper part of said wall, an annular container connected to the drum and extending downwardly in the space between said chamber and wall and spaced from said base, a hollow header, secured to the inner wall of the container and extending over the top of the furnace chamber and spaced therefrom, said header communicating with said drum, two circular series of tubes, the tubes of one series extending downwardly from the header between the combustion chamber and the container and the tubes of the other series extending downwardly from the drum between the container and said outer wall, the lower portions of the tubes in each series being connected to the lower end of the container, flues extending through the container above said header, a stack extending across the space surrounded by the drum, a damper for regulating the flow of gases through the stack, and means for blowing air and fuel upwardly in said chamber to burn the fuel in suspension therein.

2. In a steam boiler, a vertically arranged combustion chamber, open at the top and having an upwardly flaring inner surface, an outer wall spaced from and surrounding the combustion chamber and extending

above the same, a base connecting said chamber and wall, an annular steam drum, fitting within the upper part of said wall, an annular container connected to the drum and extending downwardly in the space between said chamber and wall and spaced from said base, a hollow header, secured to the inner wall of the container and extending over the top of the furnace chamber and spaced therefrom, said container having 70 passageways communicating with said header, two circular series of tubes, the tubes of one series extending downwardly from the header between the combustion chamber and the container and the tubes of 75 the other series extending downwardly from the drum between the container and said outer wall, the lower portions of the tubes in each series being connected to the lower end of the container, flues extending through 80 the container above said header, a stack extending across the space surrounded by the drum, a damper for regulating the flow of gases through the stack, and means for 85 blowing air and fuel upwardly in said chamber to burn the fuel in suspension therein.

3. In a steam boiler, a vertically arranged combustion chamber, open at the top and having an upwardly flaring inner surface, an outer wall spaced from and surrounding 90 the combustion chamber and extending above the same, a base connecting said outer wall and chamber, an annular steam drum fitting within the upper part of said wall, an annular container connected to the drum 95 and extending downwardly in the space between said chamber and wall and spaced from said base, a hollow header, secured to the inner wall of the container and extending over the top of the furnace chamber and 100 spaced therefrom, two circular series of tubes, the tubes of one series extending downwardly from the header between the combustion chamber and the container and the tubes of the other series extending downwardly from the drum between the container and said outer wall, the lower portions of the tubes in each series being connected to the lower end of the container and the ends of the tubes extending through said bottom 105 wall and being provided with caps, flues extending through the container above said header, a stack extending across the space surrounded by the drum, a damper for regulating the flow of gases through the stack, and means for blowing air and fuel upwardly in said chamber to burn the fuel in suspension therein.

4. In a steam boiler, a furnace chamber open at the top and having an upwardly flaring inner surface, an outer wall spaced from the chamber, a base connecting said wall with said chamber, an annular steam drum above the chamber, an annular container extending from the drum downwardly 115 120 125 130

around the chamber and spacer therefrom and also from said base, a header secured to the inner wall of the container and extending over the chamber, said header and container adapted to direct the gases from said chamber downwardly, thence under the container, and thence upwardly between the

container and the outer wall, and eight openings arranged in said outer wall adjacent the bottom of the container. ¹⁰

In testimony whereof I hereunto affix my signature.

JAMES POLLOCK.
